UNITED STATES PATENT OFFICE.

WILLIAM T. HOOFNAGLE, OF GLEN RIDGE, NEW JERSEY, ASSIGNOR TO THE COMFO ELECTRIC IRON COMPANY, OF GLEN RIDGE, NEW JERSEY, A CORPORATION OF NEW JERSEY.

SAFETY PLUG FOR FLATIRONS.

Application filed September 28, 1921. Serial No. 503,789.

This invention relates to improvements in safety devices for preventing the overheating of electric flat irons. In carrying out the invention, I provide a socket on or within the iron adapted to receive a plug which is outwardly the same as the threaded fuse plugs commonly used for protecting house lighting circuits. The socket is open at the bottom and when the plug is threaded into the socket 10 its base contact engages the body of the iron and is heated thereby when the iron is in use. The plug has the usual side contact, in the form of a threaded shell, which engages a similar shell within the socket. Within the 15 plug, I arrange a fusible element adapted to melt at a relatively low temperature, said element, directly engaging the base contact and adapted to be melted by the heat of the iron when the latter is left standing with the current on and becomes dangerously hot. In addition to this fusible element, I provide, within the socket, a filament which can be heated to a dull red by the electric current while the current is on and serves as a visual 20 signal to the operator, to indicate when the current is on or off. This filament and the fusible element are connected in series with the heating resistance and they may be connected in various ways with respect to one another. In the preferred arrangement, I provide in the plug an ordinary fuse wire capable of carrying the heating current for the iron and of being fused by the heat of the iron when the latter is overheated, and I arrange a lighting filament in parallel with the fuse wire. With this arrangement, the filament, which is of more expensive material 25 than the fuse, can be made very small in cross section, since it is not designed for carrying the heating current for the iron. The filament can thus be inexpensively made, and because of the small quantity of current carried by the filament the heat developed by it in the plug is negligible. When one plug burns 30 out, it can readily be replaced by another of the same kind, or, in an emergency, by an ordinary fuse plug.

In the accompanying drawing,

Fig. 1 is a top plan view of a flat iron, partly broken away, and with the upper casing and handle removed showing my invention applied thereto, the heating resistance being shown in dotted lines;

Fig. 2 is a section on the line 2—2 of Fig.

1, showing the preferred form of safety plug; 55

Fig. 3 is a vertical section through a modified form of plug; and,

Fig. 4 is a similar view showing another modification.

Referring to Figs. 1 and 2 of the drawing, 60 A represents the iron comprising a metal base 1, a heating resistance 2, resting upon the base, and a metal body 3 which rests upon the heating element and is clamped to the base in the usual manner. One end of the resistance is connected to a terminal *t* and the other end is grounded on the body 3, at *g*. In the body 3 is a recess 4, within which is arranged a socket *s*, of insulating material, having an internal annular threaded contact 70 member 5. A hollow screw plug *b* is provided with a threaded side contact 6, for engaging the contact 5, and with a base contact 7, which, when the plug is in place, rests against the metal body 3. Within the plug shown in 75 Fig. 2 is arranged an ordinary fuse wire 8, of ample capacity to carry the heating current but adapted to fuse by the heat of the iron conducted through the base contact 7, when the iron becomes excessively hot. This 80 fuse is connected in the usual manner between the side and base contacts of the plug, and in parallel with it, and similarly connected is a lighting filament 9, preferably of some non-oxidizable wire, such as platinum. This filament is proportioned so that it heats to a dull red when the current is on and serves as a signal to the operator, to indicate when the current is on. As the fuse has ample capacity 85 for carrying the current required to heat the iron, and the current passing through the filament is not required for that purpose, the filament may be made very small in cross section and proportioned to carry a very small quantity of current. Thus the cost of the filament is slight and the heat generated in the plug by the current passing through the filament is negligible. The threaded contact in the socket is connected by a conductor 10 to the terminal *t'*, and it will be evident that the 90 current flowing through the resistance and the plug from one terminal to the other will flow in parallel through the fuse and filament. 95

With the device shown in Figs. 1 and 2, if 105 the iron becomes overheated the fuse wire melts, and as this cuts off the main path for the current through the plug, the filament be-

comes heated and melts, thus cutting off the current entirely from the resistance.

In Fig. 3, I have shown an arrangement wherein a conductor 11, which may be of copper, is connected to the side contact 6 of the plug and to a body of fusible material, such as solder, which is mounted on the base contact 7, and the filament 9^a is connected in parallel with a part of the conductor. With this arrangement, the copper wire will carry the current for heating the iron, without itself becoming heated, and the filament, which may be made small in cross section, will carry enough current to cause it to become a dull red. Should the iron become overheated, the fusible connection 8^a will melt and this will interrupt the flow of current between the conductor and the base contact of the plug.

In Fig. 4, I have shown another arrangement wherein a conductor 12, of non-oxidizable material such as platinum, is connected to the side contact of the plug and to a body of fusible material 8^b on the base contact.

In this case, the conductor 12 carries the current for heating the iron and the conductor is proportioned so that it will heat to a dull red and serve as a visual signal when the current is on. If the iron becomes overheated, the fusible material melts and breaks the connection between the conductor and the base contact, thus shutting off the current from the heating resistance.

What I claim is:

In an electrically heated flat iron, a heating resistance, a metal body in series with the resistance adapted to be heated thereby, a socket on the iron adapted to receive a fuse plug, a hollow plug fitting said socket and having a base terminal engaging said body, and a fuse element and a lighting filament within the plug, said fuse element adapted to melt at a relatively low temperature and said element and filament being connected in series with said resistance.

In testimony whereof I affix my signature.

WILLIAM T. HOOFNAGLE.
